UNITED STATES PATENT OFFICE.

JOSEPH DE COSMO, OF LIEGE, BELGIUM.

TWO-STROKE EXPLOSION ENGINE.

1,413,974.

Specification of Letters Patent. Patented Apr. 25, 1922.

Application filed March 19, 1917. Serial No. 155,912.

(GRANTED UNDER THE PROVISIONS OF THE ACT OF MARCH 3, 1921, 41 STAT. L., 1313.)

To all whom it may concern:

Be it known that I, JOSEPH DE COSMO, a subject of the King of Italy, residing in Liege, Belgium, have invented certain new

5 and useful Improvements in Two-Stroke Explosion Engines; and I do hereby declare the following to be a full, clear, and exact description of the invention, such as will enable others skilled in the art to which it applies 10 to make and use the same, reference being had to the accompanying drawings, and to letters or figures of reference marked therein, which form a part of this specification.

15 The invention relates to a two-stroke explosion engine of the type wherein the driving piston has a sleeve-like extension or liner in which moves a special scavenging piston, that is a piston chiefly designed to expel 20 the burnt gases.

The drawing annexed to the present specification illustrates by way of example a form of a two-stroke engine or motor with four cylinders constructed according to the above 25 indicated principle, the cranks being secured at 90°.

Figure 1 shows the engine in section on the line C—D of Figure 2 and shows the scavenging piston at the middle of the exhaust.

Figure 2 is a section on A—B of Figure 1.

Figures 3 to 7 are axial cross-sections illustrating different forms of the scavenging piston according to my invention.

35 In the cylinder 1, provided with openings for admission 2 and exhaust 3, moves a piston 4, receiving a reciprocating movement from the connecting rod 5 which is connected to the crank end shaft 6. The piston 4 is surrounded by a liner 7 having inlet and exhaust ports 8 and 9. In the piston 4 slides a scavenging piston 10 supported by a rod 11 which is guided in the end of the rod of piston 4. The piston 10 is provided with a 40 circular row of small check valves 12 arranged horizontally as shown on a larger scale in Fig. 5.

The drive of the scavenging piston is performed as follows: the sheaves or flanges of 50 the crank shaft 6 are provided with cam surfaces 13 and 14, one of which acts upon the roller 15 for the ascent of the scavenging piston, and the other upon the roller 16 for the descent of the scavenging-piston. To this end these rollers 15 and 16 are supported

by arms 17 and 18 mounted upon an axle 19 which serves as a journal for a lever 20 sliding in a groove 21 made in the lower part of the rod 11 of the scavenging piston.

The head 22 surmounting the cylinder 10 regulates the space reserved to the compression or delivery chamber; it receives the spark plug 23.

To illustrate the distribution mechanism, let us suppose that the compressed gases 65 have just been exploded; under the action of the expansion of these gases the scavenging piston 10 goes down, bearing upon the piston 4, which, at a given moment, a little before it arrives at its lower dead-center, begins 70 to uncover the exhaust openings 3 of cylinder 1 by means of the ports 9 of its liner 7. The exhaust of the burnt gases begins and is soon hastened by the ascent of the scavenging piston 10, under the action of the contact of the 75 cam 13 with roller 15. As the profile of cam 13 is so calculated that the scavenging piston comes at stroke-end up to 1 mm. of the head, the exhaust of burnt gases may be considered to be complete.

On the other hand, the movement of the scavenging piston takes place smoothly and without shock, owing to the fact that one half of stroke is accomplished in a uniformly accelerated movement, and the other 80 half in a uniformly retarded movement. Further the pressure of burnt gases upon the scavenging piston during its ascent is as it were null, as the exhaust openings 3 are wide open before the scavenging piston begins to 85 rise.

On its downward movement moreover the driving piston 4 placed its ports 8 opposite to admission openings 2 of the cylinder, but the ports 8 remained covered by the scavenging piston 10, until the latter began to rise. While expelling the burnt gases, as just pointed out, the scavenging piston 10 has uncovered the ports 8, thus allowing fresh gas to rush into the space between the two 90 pistons. At a given time the driving piston, on its upward stroke, covers again the exhaust openings of the cylinder and closes completely the admission of fresh gases, which are thus kept or confined between the 105 walls of the liner, the bottom of the scavenging piston, which has arrived at its upper stroke-end, and the upper face of the driving piston. Then the cam 14 begins to thrust upon the roller 16 and the scavenging piston 110

goes down to meet the driving piston. Under effect of the pressure of the gases which are compressed by the two pistons moving in opposite directions, the valves 12 open automatically and make way for the gases flowing to the explosion chamber.

On continuing their stroke the driving and scavenging pistons will meet each other, but this meeting takes place without shock, 10 first because the profile of the cam 14, like that of cam 13, is so calculated that the downward movement of the scavenging piston be first accelerated and then retarded, and also because a little before the pistons 15 meet each other the cam 13 acts again upon the roller 15 and the piston 10 rises again at a lower speed than the driving piston. Thus this meeting, that causes the closing of the valves 12, takes place while both pistons 20 move in the same direction; both acting as a single piston, compress the gases while rising. These gases are then normally ignited by the spark plug 23, when the driving piston has arrived at its upper dead-center. When the explosion has taken place, 25 both pistons are driven downward, the scavenging piston bearing on the driving piston, until the scavenging piston alone rises again to expel the burnt gases and to draw in the fresh gases, as explained just above.

Figure 3 shows a modification in which the valve 24, which performs the same function as the check-valves 12, is adapted to be operated concurrently with the scavenging piston 10. To this end the valve 24 is secured to a rod 30 slidably mounted in the rod 11 of the scavenging piston. Opposite the slot 21 in rod 11 is a slot 31 in rod 30, through which the lever 20 is adapted to extend when in engagement with slot 21, the relative arrangement of lever 20 and rod 11 being the same as in Fig. 1. Slot 31, however, is shorter than slot 21, so that when the lever 20 moves upwardly its action is first to lift the valve 24 until it engages its seat 25 and prevents the passage of fluid through the piston 10. When the scavenging piston again moves downwardly and the exhaust and admission have taken place, the valve 24 uncovers the ports 32 in the scavenging piston and both the valve 24 and piston 10 continue their downward movement until piston 10 comes to rest on the working piston. Compression then takes place as described with reference to Figs 1 and 2.

I have already pointed out the numerous advantages procured by this engine with respect to dynamics, but its superiority is also established in regard to mechanics.

60 The auxiliary shafts, cam shafts and crank

shafts driving the distribution pieces and their pinions have been dispensed with. Moreover, the distribution being controlled solely by the two pistons, the suction and exhaust pipes as well as the inlet and outlet pipes for water may be cast in one piece with the cylinder, so that the structure combines a great strength with a neat appearance while a great power or efficiency is secured for a small space occupied.

Having thus described the invention, what I claim is:

1. In a two-stroke explosion engine, the combination with a cylinder provided with inlet openings at the lower part and with 75 exhaust openings at the upper part, of a driving piston, a liner carried by said driving piston, said liner being also provided with inlet and exhaust openings, a scavenging piston moving within the driving piston, 80 a valve controlling an opening in said scavenging piston, a rod for said scavenging piston extending through the driving piston and guided by the latter, said rod being provided with a recess, a lever extending into that recess, a pair of rollers carried by said lever, a crank shaft, and cam surfaces on the sheaves of said crank-shaft adapted to act upon said rollers to control the ascent and the descent of the scavenging piston. 90

2. In a two-stroke explosion engine, the combination with a cylinder provided with inlet openings at the lower part and with exhaust openings at the upper part, of a driving piston, a liner carried by said driving 95 piston, said liner being also provided with inlet and exhaust openings, a scavenging piston moving within the driving piston, a valve controlling an opening in said scavenging piston, a rod for said scavenging piston 100 extending through the driving piston and guided by the latter, said rod being provided with a recess, a lever extending into that recess, a pair of rollers carried by said lever, a crank shaft, and cam surfaces on the sheaves of the said crank-shaft adapted to act upon said rollers to control the ascent and the descent of the scavenging piston, said cams having such a profile that the meeting of the driving piston and the 110 scavenging piston occurs always when both the pistons are moving in the same direction.

In testimony that I claim the foregoing as my invention, I have signed my name in presence of two subscribing witnesses.

JOSEPH DE COSMO.
